UNITED STATES PATENT OFFICE.

JOSEPH H. WESSON, OF SPRINGFIELD, MASSACHUSETTS.

GUN-LOCK.

SPECIFICATION forming part of Letters Patent No. 243,183, dated June 21, 1881.

Application filed April 13, 1881. (No model.)

To all whom it may concern:

Be it known that I, JOSEPH H. WESSON, of Springfield, in the county of Hampden and State of Massachusetts, have invented a new and useful Improvement in Self-Cocking Double Guns, of which the following is a specification and description.

The object of my invention is to obviate the necessity of cocking the hammers of double guns with the thumb each time it is desired to discharge one of the barrels, and to accomplish the said cocking of the hammers or moving back of the exploding-piece by the movement of the trigger alone, and I obtain this result by the mechanism substantially herein-after described, and illustrated in the accompanying drawings.

Figure I is a side view of a double breech-loading fire-arm made according to my invention. Fig. II is a horizontal longitudinal section of the same at line D. Fig. III is a side view of the lock mechanism. Fig. IV is a vertical section of the trigger and a portion of the two sears at line F of Fig. III. Fig. V is a vertical transverse section of the two auxiliary tumblers and the pivot or trunnion which connects them, with the hammer-tumblers and their stirrups in place thereon. Fig. VI is a side view of the auxiliary tumbler, and Fig. VII is a front view of the two auxiliary tumblers and the pivot or trunnion which connects them, and upon which they revolve.

In the drawings, A represents the frame of a double gun having a longitudinal central plate, A', to which the lock mechanism is secured.

E denotes the breech-plate, and B the two barrels.

1 denotes an auxiliary tumbler, having a pivot or trunnion, as 16, which may be of any desired size having a bearing in a hole in or through the middle plate, A', one of said tumblers on each side of the plate A', and one may be made solid with the pivot or trunnion 16, and the other connected therewith or secured thereto by screws or pins, as shown clearly in Fig. V. Each auxiliary tumbler 1 is provided with a series of notches, as 2, each notch in either auxiliary tumbler being located opposite a point midway between two notches in the other auxiliary tumbler, as shown in full lines, and in dotted lines in Figs. I and VI.

A hammer, 14, of any desired form, and adapted to operate either outside or inside the frame, is provided at its lower part with the tumbler, as 5, and with a pivot-stud, as 6, either made solid therewith or separate, which pivot-stud may have a bearing at one end in the trunnion 16, and at the other end, if desirable, in the lock-plate, in such a manner that both the auxiliary tumblers 1 may revolve independently of either hammer-tumbler.

A stirrup, as 4, is pivoted to the rear part of the hammer-tumbler 5, whose upper end has a bearing in the hooked end of the mainspring 20, and whose lower end is somewhat elongated below its pivot, and bears against the inside of the slot 17 when the nose of the hammer is against the firing-pin, causing the upper end of the stirrup to ride up the incline of the hook at the extremity of the mainspring, which construction operates to move the hammer back a little or rebound it from its contact with the fire-pin. This particular rebounding feature of the lock mechanism is not, however, a part of my invention, and needs no further description here.

The rear part of the tumbler 5 may be made of any desired form, and is provided with a notch, as 3, located at the same distance from the axis of the tumbler 5 as the notches 2 are distant from the axis of the disk 1, both axes being coincident.

In the lower part of the frame A, and beneath the middle plate, A', is pivoted the trigger 9, with a trigger-spring, as 8, in the frame, engaging with the rear part of the trigger to hold its front part in its most elevated position.

Two sears or dogs, as 7, are pivoted in the forward and upper part of the trigger, these sears being forked or extending outward each way at their upper end, so that the catch on the upper end of each will impinge against one of the hammer-tumblers, and also the auxiliary tumbler by its side, and a small stud or pin, as 12, projects out from the plate A' on each side in front of each sear 7, and a spring, as 11, operates to hold the catch on the upper end of the sear into engagement with the notch 3 in the hammer-tumbler 5.

The auxiliary tumbler 1 should be fitted in its bearings, so that it will turn with sufficient friction to remain in any position into which

it may be turned, even while the hammer is moving.

The firing-pin 15 is secured in the breech-plate at the rear end of each barrel, with its actuating-spring, in the usual manner, and projects rearward to a point in front, and within reach of the nose of the hammer or exploding-piece.

- The operation of my invention is as follows:
- 10 The illustration in Fig. I shows the parts as they are in the gun when not in use, in which case one of the sear-catches is engaged in the notch 3 of the hammer-tumbler 5, and also with the notch 2 in the auxiliary tumbler 1 by its side, both these notches forming substantially one notch when they coincide, with both of which the catch of one sear will engage. If the trigger be pulled backward, both sears 7 will be drawn down, the catch of the sear
  - 15 20 which is not in engagement with the tumbler-notch riding down against the periphery of the auxiliary tumbler on that side as the latter revolves. The sear on the opposite side, however, whose catch is in engagement with the notch of the corresponding hammer-tumbler 5, draws down that part of the hammer-tumbler, and also revolves the auxiliary tumbler until, as the sear moves down far enough, it impinges against the projecting stud 12, which throws
  - 25 30 the sear-catch out of engagement with the notch 3 of the hammer-tumbler, and also out of engagement with the notch 2 in the auxiliary tumbler and the hammer, made upon or connected with the tumbler 5, actuated by its mainspring 20, quickly moves forward against the fire-pin 15 and explodes the charge, the auxiliary tumbler 1 remaining in the position where it was left when released by the sear. As the tumbler 5 and its hammer moved
  - 35 40 forward to explode the charge the notch 3 in the hammer-tumbler on that side moved up to a point between two adjacent notches 2 in the disk 1, so that as that sear moves up again on releasing the trigger its catch rides against the periphery of the disk or auxiliary tumbler 1, and cannot enter the notch 3 of that hammer-tumbler. As the two auxiliary tumblers 1 are connected together and revolve together, the movement of the sear just described, in
  - 45 50 discharging the arm, revolved the auxiliary tumbler 1 of the other lock, so as to bring one of the notches 2 therein into a position by the side of or coincident with the notch 3 in that hammer-tumbler 5, so that when the pressure
  - 55 60 against the trigger is released the catch of that sear rides up against the tumblers on that side until it enters the coincident notches therein, which occurs when the trigger has moved to its forward position. The sear, which in this last movement downward revolved the hammer-tumbler and moved the hammer to discharge the arm in its movement upward, rides upon the periphery of its auxil-

iary tumbler 1, but cannot enter the notch 3 in the corresponding hammer-tumbler, as the latter does not coincide with the notch 2 in its auxiliary tumbler, and therefore when the trigger is again pulled that disengaged sear rides down on the periphery of the auxiliary tumbler on that side, while the engaged sear on the opposite side draws down the hammer-tumbler 5 and raises the hammer, and, impinging against the stud 12 on that side, releases the hammer, which is forced forward by its mainspring to strike the fire-pin. In this manner the two auxiliary tumblers 1 are given an intermittent rotary movement, so that the notches 2 therein are alternately brought into a position coincident with the notch in the hammer-tumblers 5, and the hammers are alternately operated to discharge the arm by the simple successive movements of the trigger backward, and without other manipulation of the arm, except to insert the cartridges.

If it should be desired to make a differently-moving hammer, or a hammer made separate from its tumbler 5, which might involve a change in location of the parts, as well as a change in form, it might be done without departing from the invention. For example, the notches in the auxiliary tumblers or disks 1 might be reversed, and in some classes of arms it might be desirable to locate the auxiliary tumblers and the hammer-tumblers in such relative position to the trigger that the latter would be elongated in rear of the pivot on which it swings in the frame instead of in front, and the sears 7, pivoted to this rearward elongation, so as to push against the notches in both tumblers when the trigger was pulled, instead of pulling against them, as above described.

It is evident that instead of the notches 2, made in the periphery of the disk or auxiliary tumbler 1, elongated bosses or projections may be made on the side of each disk, near the periphery, to answer the same purpose.

Having thus described my invention, what I claim as new is—

The combination, in a double gun, of two disks or auxiliary tumblers, one on each side of the frame, and both connected so as to rotate together, and each provided with notches in its periphery, any one of which notches is equidistant from two adjacent notches in the opposite disk, two hammer-tumblers adapted to vibrate in connection with the auxiliary tumblers or disks, and each connected with a hammer for exploding the charge, and each operated by a sear pivoted to a single trigger, substantially as described.

JOSEPH H. WESSON.
